[57] **CLAIM**

The ornamental design for a radio receiver, as shown and described.

DESCRIPTION

FIG. 1 is a perspective view of a radio receiver showing my new design;

FIG. 2 is a front elevational view of the end shown on the left in FIG. 1;

FIG. 3 is a front elevational view of the end shown on the right in FIG. 1;

FIG. 4 is a side elevational view broken away for convenience of illustration;

FIG. 5 is a bottom plan thereof;

FIG. 6 is a partial top plan view of the FIG. 2 end of the receiver; and

FIG. 7 is a partial top plan view of the FIG. 3 end of the receiver.

FIG. 1

FIG. 2

FIG. 3
